(57) **CLAIM**

The ornamental design for a lamp, as shown and described.

DESCRIPTION

FIG. 1 is a perspective view of a lamp showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof; and

FIG. 8 is another perspective view showing the lamp.

FIG. 9 is a perspective view showing the lamp in use.

FIG. 10 is a perspective view showing the lamp not in use; and,

FIG. 11 is a perspective view showing the lamp in another use. The broken lines shown represent unclaimed subject matter and form no part of the claimed design.
